MEANS FOR TAPPING A HIGH PRESSURE
LINE OR CONTAINER

Louis G. Hooper, Sarepta, La., assignor to The
Bastian-Blessing Company, Chicago, Ill., a cor-
poration of Illinois

Application December 31, 1935, Serial No. 57,039

1 Claim. (Cl. 29—84)

This invention relates to a means for tapping a high pressure line and container without lowering the pressure or losing any of the fluid, the general object of the invention being to first bore a hole in the line or container without loss of pressure of fluid and to insert a tube in the line or container for withdrawing some of the fluid or inserting fluid, and to provide for removing the various parts after the above operation has been completed without loss of pressure or fluid.

Another object of the invention is to so construct the withdrawal means that such means can not be rendered active without the use of special equipment so that there is no danger of an unauthorized person tampering with said means.

Another object is to provide a means for automatically keeping a pipe line free of condensed liquid.

Another object is to provide a means for installing a siphon in a pipe line against pressure in such a manner that it is unnecessary to leave on the pipe line a conventional valve for closing the siphon when the same is not in use.

The invention together with its objects and advantages will be best understood from a study of the following description taken in connection with the accompanying drawings wherein:

Figure 1 is a longitudinal sectional view with parts in elevation showing the line or container tapped and the siphon means in position, but with the valve closed to prevent siphoning action.

Figure 2 is a similar view showing the parts for opening the valve to permit the siphoning action.

Figure 3 is a view of a drill which may be used with the invention.

Figure 4 is a view of a plug used to close the tapped part of the line or container when the siphoning equipment is not in place.

Figure 5 is a vertical sectional view partly diagrammatic showing an accumulating chamber connected with the line or container.

Figure 6 is a section on the line 6—6 of Figure 5.

Figure 7 is an enlarged detailed sectional view illustrating the details of the lower end of the siphon tube and

Figure 8 is a section taken on the line 8—8 of Figure 7 and looking downwardly.

In the drawings the letter A indicates a gas line although it is to be understood that the device can be used with any suitable fluid container.

The first part of the operation for carrying out the invention is the welding of a nipple 1 to the line as shown at 2. (Fig. 1). The nipple 1 is threaded interiorly and exteriorly as shown.

Next, a valve casing 3 is threaded to the exterior of the nipple, and this casing contains a valve 4.

A pressure barrel 5 is threaded to the valve casing and a hollow head 6 is threaded to the opposite end of the barrel. This head is provided with an outlet 7 controlled by a valve 8. The top of the head is provided with a threaded opening for receiving the stuffing box 9 which carries the packing nut 10.

Figure 3 shows a drill 12a having a stem 12 which may be used for tapping the line, but it is to be understood that any form of drill can be used, such for instance as the cup type. The stem of the drill is passed through the packing means 9 and 10 before the same are screwed into the head 6, and the drill 12a is then passed downwardly through the head 6, barrel 5 and valve casing 3 to the nipple 1. A handle such as is shown at 13 has a square member therein to receive the squared part 14 of the drill which member is part of a ratchet mechanism by means of which the handle 13 may be freely moved back and forth to rotate a part received within said member and a pulley carrying yoke 15 is placed on the part 16 at the upper end of the drill stem and then a nut 17 threaded on the threaded part 18 of the drill stem.

The head 6 carries the extensions 19 which rotatably support the drum 20 provided with the ratchet 21 engaged by the dog 22 carried by the upper end of a handle 23 so that by operating the handle the dog 22 engages the ratchet 21 and will rotate the drum.

A cable 24 has one end attached to the drum and said cable is adapted to be passed over the pulleys 25 of the yoke, and then the cable is attached to the outlet 7 of the head 6 as shown at 26.

The drum 20 is turned by the handle 23 which causes the cable to apply pressure to the drill and at the same time the drill is turned by the handle 13 until the bit penetrates the line A. During this operation the valve 8 is closed and the stuffing box 9 and 10 is adjusted to prevent leaks around the drill stem. The drill stem is rotated until it can be forced inwardly by the drum assembly without rotating the handle and when this can be done drilling of the hole has been completed. Then the dog 22 is raised out of engagement with the ratchet 21 to permit pressure in the line to force the drill stem out of the pressure barrel 5. Then valve 4 is closed and valve 8 is open and this completes the tapping of the line.

The stuffing box and the drill are then removed and the stuffing box placed on a tube 27 and the

lower end of this tube is connected by the bushing 30, acting as a coupling, to the upper end of the siphon tube 29.

Slightly above the lower end of the tube 29, 5 said tube is formed with ports 31, and the lower portion of the tube 29 is received within a short tube 32 which extends downwardly beyond the lower end of the tube 29 and is provided at its lower end with projections 33.

10 As best shown in Figure 7 a split band 11 embraces a lower portion of the tube 29 above the ports 31 and at intervals the upper portion of the tube 32 is welded to the band 11 as at 11a. A gasket 32a or the like is provided to form a seal 15 between the upper end of the tube 32 and the exterior of the tube 29. Also, a plug 36 is threadedly engaged within the lower part of the tube 29 so that it may be moved to a position either above or below the port 31, and has a non-circular part 20 37 at its upper end whereby it may be rotated to one position or the other in a manner hereafter to be set forth. This plug when the parts are assembled as described occupies its position above the port 31 and thus serves as a closure for the 25 tube 29.

The tubes 27 and 29 thus assembled are passed downwardly through the head 6, and barrel 5 and into the valve casing with the lower end of the tube 32 resting on the closed valve 4 and the packings 9 and 10 are threaded tight into the upper 30 end of the head 6.

A member 34 is shaped like the upper end of the drill 12 and is connected with the upper end of the tube 27 by a sleeve 35 and the handle 13 and 35 yoke 15 are connected with the member 34, with the drum and cable arranged as shown in Figure 1.

The valve 8 is closed and valve 4 opened and then the drum is turned to cause the cable to move the tube downwardly until the bushing 30 engages with the internal thread of the fitting 1. 40 Then the tubes are turned by the handle 13 until the bushing 30 is tightened in fitting 1 and the tube 32 at the lower end of the tube 29 comes in contact with the bottom of the line A as shown 45 in Fig. 1a. The valve 8 is then opened and the yoke and the associated parts are removed from the upper end of the tube 27 by unscrewing the collar 35. The packing means are loosened and then the parts 6, 5 and 3 are removed after which 50 the bushing 30 will be held and the tube 27 unscrewed therefrom.

It will of course be understood that no fluid can escape from the line at this stage as the plug 36 closes the lower end of the tube 29.

55 When it is desired to remove liquid or the like from the line a nipple 38 (Fig. 2) has one end threaded into the plug 36 and a valve 40 is threaded to the upper end of the nipple 38 while a tube 41 is threaded to the valve. The tube 41 60 has a packing 42 at its upper end and an outlet 43 controlled by a valve 44.

A rod 45 is passed through the packing 42 and a handle 46 is attached to the upper end of the rod, the lower end of the rod being enlarged and 65 formed with a socket 47 which is made to fit the non-circular part 37 of the plug 36. The rod is passed downwardly into the tube 29 to engage the socket 47 with the part 37 of the plug and then the valve 44 is closed and the packing 42 70 tightened to prevent leakage.

The rod 45 is then turned by the handle 46 to cause the socketed part to rotate the plug 36 whereby said plug is moved downwardly below the ports 31 and to substantially the position suggested in Figure 7. The pressure will then raise 75

the rod 45 until the socketed part rises above the outlet 43. The valve 40 is then closed and the valve 44 opened after which the tube 41 with the rod 45 is removed. If desired to remove liquid or the like in the line the valve 40 can be opened so that the pressure in the line will force the liquid through the tube 29 and practically all of the liquid in line will be blown therefrom. 5

If the automatic trap shown at B in Figure 5 is to be used the trap is placed adjacent to the 10 line and an elbow 47a is connected with the valve 40 before said valve is opened and a conduit 48 is connected with the elbow 47a and leads into the tank or accumulating chamber 49. The tank contains a float valve 50 and a discharge pipe 51 15 which has a port 52 therein controlled by valve 53 carried by a depending part of a link 54 pivoted to the pipe 51 and to a depending part of the float. The lower end of the pipe 51 is open and has a sleeve 55 thereon which is similar to the sleeve 20 or short tube 32 so that practically all the liquid in the tank can be blown therefrom.

By opening the valve 40 the liquid in the line will discharge into the tank and when the liquid in the tank reaches a certain level it will raise the 25 float and thus the valve 53 will be open so that the liquid will pass through the discharge pipe 51. Any liquid accumulating in the line above the bottom of the siphon will be forced over into the trap when an increase in pressure occurs that is 30 greater than the weight of the liquid in the tube 29. As the level of the liquid in the tank drops the float will move downwardly and close the valve 53.

When it is desired to remove the siphon and trap 35 the valve 40 is closed and the elbow 47a removed therefrom. The tube 41 and rod 45 are put back in place as shown in Figure 2 and then valve 44 is closed and valve 40 opened to permit the rod 45 to pass therethrough into the tube 29 to engage the plug 36. The rod is then turned to move the plug above the port 31. Then the valve 44 is opened, the rod 45 raised and all the parts including the valve 40 are removed. Then the tube 38 is removed while the bushing 30 is held 45 to prevent its removal. Then tube 27 is threaded into the bushing 30 and the bushing 30 loosened slightly from its engagement with the fitting 1, after which valve 3, barrel 5 and the parts attached to the barrel as shown in Figure 1 are put 50 back in place. Then the tubes 27 and 29 are rotated by the handle 13 to completely unscrew bushing 30, already loosened, from the internal threads of the fitting 1. Of course in this operation the valve 8 is closed and after the plug 30 55 has been unscrewed from the nipple the drum is slowly turned to release the cable 24 to permit pressure to raise the siphon tube 29 until the bottom of the siphon tube passes the valve 4. Then the valve 4 is closed and valve 8 opened. Stuffing 60 box 9 may then be unscrewed and removed, together with tube 27, bushing 30 and siphon tube 29. Then tube 29 and bushing 30 are removed from the tube 27 and a plug such as shown at C in Figure 4 is threaded on the lower end of the 65 tube 27 and the tube 27 with the plug C and stuffing box 9 are replaced in barrel 5. After closing of valve 8 and opening of valve 4, tubing 27 may again be rotated to thread the plug C into the upper end of the nipple 1. Then the valve 8 70 is opened and the parts 3, 5 and 6 lifted slightly, whereupon the plug C may be held and tube 27 rotated to permit removal of the entire apparatus excepting fitting 1 and plug C. Then a protection cap can be threaded on to the fitting 1. The 75

needle valve in plug C, which is preferably slightly unseated during the installation or removal of this plug to permit a balancing of the pressure in the line A and the barrel 5, is tightened after 5 installation.

Thus I have provided a means for tapping a pipe line or container without loss of fluid and siphoning fluid therefrom and then removing all the parts excepting the fitting 1 which is closed 10 by the plug C and by a cap, when desired.

Of course the invention can be used for inserting fluid into the line or container.

Having thus described the invention, what is claimed as new is:

15 A pipe line tapping mechanism comprising a valve assembly adapted to be connected to a pipe line for controlling flow of fluid therefrom, casing means defining a chamber in line with said valve assembly and connected to the latter, a tool 20 mounted in the upper end of said casing for rotary and longitudinal movement with respect thereto,

said tool having one end exposed exteriorly of said casing and the other end enclosed by and movable within said casing and valve assembly into operative engagement with the pipe line, fluid sealing means between the casing and said tool, means carried by the exposed end of the tool for rotating the same, a strap member having one of its ends anchored exteriorly of said casing, a strap guide mounted upon the exposed end of the tool for rotation about the longitudinal axis of the tool, 10 and strap winding means carried by the casing and connected to the other end of the strap, the intermediate portion of the strap passing over said strap guide whereby the expanse of strap between the anchored end thereof and said strap 15 winding means may be reduced by said winding means while the tool is being rotated, to thereby simultaneously rotate the tool and crowd it toward the pipe line.

LOUIS G. HOOPER. 20
